The ornamental design for a cable connector, as shown and described.

DESCRIPTION

FIG. 1 is a front, top, and left perspective view of a first embodiment of a cable connector, showing my new design. FIG. 2 is a front view of the first embodiment of the cable connector of FIG. 1.

FIG. 3 is a rear view of the first embodiment of the cable connector of FIG. 1.

FIG. 4 is a left side view of the first embodiment of the cable connector of FIG. 1.

FIG. 5 is a right side view of the first embodiment of the cable connector of FIG. 1.

FIG. 6 is a top view of the first embodiment of the cable connector of FIG. 1.

FIG. 7 is the bottom view of the first embodiment of the cable connector of FIG. 1.

FIG. 8 is a front, top, and left perspective view of a second embodiment of the cable connector, showing my new design.

FIG. 9 is a front view of the second embodiment of the cable connector of FIG. 8.

FIG. 10 is a rear view of the second embodiment of the cable connector of FIG. 8.

FIG. 11 is a left side view of the second embodiment of the cable connector of FIG. 8.

FIG. 12 is a right side view of the second embodiment of the cable connector of FIG. 8.

FIG. 13 is a top view of the second embodiment of the cable connector of FIG. 8.

FIG. 14 is the bottom view of the second embodiment of the cable connector of FIG. 8.

(Continued)

FIG. 15 is a front, top, and left perspective view of a third embodiment of the cable connector, showing my new design.

FIG. 16 is a front view of the third embodiment of the cable connector of FIG. 15.

FIG. 17 is a rear view of the third embodiment of the cable connector of FIG. 15.

FIG. 18 is a left side view of the third embodiment of the cable connector of FIG. 15.

FIG. 19 is a right side view of the third embodiment of the cable connector of FIG. 15.

FIG. 20 is a top view of the third embodiment of the cable connector of FIG. 15; and,

FIG. 21 is the bottom view of the third embodiment of the cable connector of FIG. 15.

The broken lines in the drawings show portions of the cable connector that form no part of claimed design.
